Primary Examiner — Darlington Ly*Assistant Examiner* — Jeremy Koenig(74) *Attorney, Agent, or Firm* — Womble Bond Dickinson (US) LLP(57) **CLAIM**

The ornamental design for a wheel, as shown and described.

DESCRIPTION

FIG. 1 is a perspective view of a wheel according to my new design;

FIG. 2 is a front elevational view thereof; and,

FIG. 3 is a side elevational view thereof.

The broken lines depict portions of the wheel that form no part of the claimed design.
